CLAIM

The ornamental design for a housing for a printer system, as shown and described.

DESCRIPTION

FIG. 1 is a perspective view of a housing for a printer system showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof;

The broken lines in FIG. 1 are for illustrative purposes only and form no part of the claimed design.

FIG. 1.

FIG. 5.

FIG. 2.

FIG. 4.

FIG. 6.

FIG. 7.

FIG. 3.
